(57) **CLAIM**

We claim, the ornamental design for a training card, as shown and described.

DESCRIPTION

FIG. 1 is a top plan view of a training card showing our new design, the bottom plan view being a mirror image thereof; FIG. 2 is a first side elevation view of the training card, the opposite side being a mirror image thereof;

FIG. 3 is a front view of a first embodiment of the invention, the top plan view and the side elevation view being the same as FIG. 1 and FIG. 2 respectively;

FIG. 4 is a rear view of the first embodiment of the invention;

FIG. 5 is a front view of a second embodiment of the invention, the top plan view and the side elevation view being the same as FIG. 1 and FIG. 2 respectively;

FIG. 6 is a rear view of the second embodiment of the invention;

FIG. 7 is a front view of a third embodiment of the invention, the top plan view and the side elevation view being the same as FIG. 1 and FIG. 2 respectively;

FIG. 8 is a rear view of the third embodiment of the invention;

FIG. 9 is a front view of a fourth embodiment of the invention, the top plan view and the side elevation view being the same as FIG. 1 and FIG. 2 respectively;

FIG. 10 is a rear view of the fourth embodiment of the invention;

FIG. 11 is a front view of a fifth embodiment of the invention, the top plan view and the side elevation view being the same as FIG. 1 and FIG. 2 respectively; and,

(Continued)

FIG. 12 is a rear view of the fifth embodiment of the invention.

The dashed lines shown in FIGS. 1-12 indicate the outer perimeter of the training card and form no part of the claimed design.
